Patented Jan. 6, 1976

238,401

CONTAINER FOR A TAPE CASSETTE

Peter Ackeret, Kusnacht, Switzerland, assignor to IDN
Inventions and Development of Novelties AG, Lenzer-heide, Switzerland

Filed Oct. 12, 1973, Ser. No. 406,169

Term of patent 14 years

Int. Cl. D3—02

U.S. Cl. D87—1 D

Fig.1

FIG. 1 is a front, top and right side perspective view of a container for a tape cassette showing my new design;
FIG. 2 is a front, bottom and left side perspective view;
FIG. 3 is a view similar to FIG. 1 showing the container in open condition; and
FIG. 4 is a rear elevational view.

I claim:

The ornamental design for a container for a tape cassette, as shown and described.
